CINDER DEFLECTOR

Emanuel Rawson, Chicago, Ill., assignor to The
Superheater Company, New York, N. Y.

Application August 28, 1943, Serial No. 500,336

5 Claims. (Cl. 122—462)

The present invention relates to heat exchange apparatus and particularly to superheaters installed in fire tube boilers such as utilized on locomotives.

In locomotive boilers the superheater tubes project forwardly from the flues into the smoke box where they are bent upwardly for connection to the superheater headers that are located forwardly of the front tube sheet of the boiler. It has been customary to provide the bent portions of the superheater tubes with shields facing the tube sheet and designed to minimize cutting of the tubes by cinders ejected from the flues in which the tubes are located. It has been found, however, that where the superheater flues are interspersed among the fire tubes considerable cutting of the tubes along the sides of the bent parts which are not protected by these shields result from the cinders that are ejected from fire tubes positioned between the flues in which the superheater tubes are located. The present invention contemplates the provision of tubular cinder deflectors so mounted with respect to the forward ends of the fire tubes of the boiler as to direct and control the path of travel of the cinders ejected from the tubes and thus maintain them away from the sides of the upwardly extending parts of the superheater tubes.

The invention will be best understood upon consideration of the following detailed description of illustrative embodiments thereof when read in conjunction with the accompanying drawings in which:

Figure 1 is a fragmentary longitudinal section of the forward portion of a locomotive boiler having a superheater equipped with cinder deflectors embodying the present invention.

Figure 2 is a partial front view of the superheater as viewed from the right in Fig. 1 and

Figures 3 and 4 are views similar to Figures 1 and 2, respectively, showing a modified form of cinder shield.

Referring first to Figures 1 and 2, the numeral 10 designates the front tube sheet of a locomotive boiler having a plurality of fire tubes and superheater flues disposed in both vertical and horizontal alignment to form a plurality of rows with the fire tubes 11 interspersed among the flues 12. Mounted within each of the flues 12 is a looped superheater unit designated as a whole by the numeral 13 having its end portions projecting forwardly into the smoke box from the flues for connection to the saturated and superheated steam chambers of a header 14 mounted forwardly of the tube sheet 10 and

somewhat above the top row of flues 12. To connect the end portions of the superheater units with the header the tubes are appropriately bent at 15 so that the units may be connected to the header 14.

As mentioned above, it is customary to provide shields 16 on the bent portions 15 of the superheater tubes facing the flues 12 so as to protect the rear and part of the side faces of the bent portions of the tubes from erosion by cinders that are ejected with considerable force along with the gases discharged from the flues.

In installations where fire tubes 11 are interspersed among the flues 12 the cinders ejected from the fire tubes spread out conelike in all directions on entering the smoke box and some therefore impinge against the sides 17 of the bent and upwardly extending portions 15 of the superheater units and cause erosion or "cinder cutting" of these parts of the superheater tubes especially where the ligament between adjacent flues is less than the fire tube diameter. To correct for this condition the present invention

contemplates the provision of tubular cinder deflectors designated as a whole by the numeral 18 and consisting of a cylindrical section 20 of suitable size to be inserted with a close fit in a fire tube 11 to which it may be welded if desired. Forwardly of the tube sheet 10 the deflector 18

is formed with an elongated somewhat elliptical portion 21 formed by flattening a tubular section so that the forward part of the deflector 18 may be disposed in a vertical position intermediate adjacent bent portions 15 of the superheater tubes that are located in adjacent flues. As shown in Figure 1 the flattened portion 21 of the deflector 18 is of such length as to extend forwardly between all of the bent portions 14 of the tubes forming the superheater with the result that the cinders ejected with the gases from the fire tubes 11 are carried to a point beyond the bent portions 15 of all the superheater tubes.

However, the forward end of the flattened portions 21 of the deflectors 18 may be located rearwardly of the position shown as, for example, in a plane just rearwardly of the bent portion 15 of the uppermost superheater unit as indicated by the dotted line "A" in Fig. 1. The location of the forward end portion of the deflectors 18 depends upon the length required to impose a fixed direction and path of travel upon the gases and cinders emerging from the tubes 11 so as to maintain them in their path of travel at least until they pass beyond the most forwardly located superheater tube portions 15 in order to avoid impingement thereon.

45

50

55

In the form shown in Figures 3 and 4 the deflecting shields 30 are mounted forwardly of the tube sheet 10 facing the forward end of the fire tubes 11 and in position to receive the stream of gas and cinders discharged from the tubes. Each deflector is provided with bell mouth 31 to facilitate diversion of the cinders into the deflector 30. The deflectors 30 for any vertical row of fire tubes are aligned and interconnected by vertically disposed web-like plates 32 with the uppermost and lowermost deflectors connected to brackets 33 and 34 for supporting several interconnected deflectors in positions where they may receive the cinders discharged from the related flues. In this form the deflectors 30 are tubular throughout their length and extend forwardly among adjacently disposed bent portions 15 of the superheater tubes to positions clear of the most forwardly located superheater tubes at the level of each deflector. As in the case of the arrangements of Figures 1 and 2, the deflectors may, however, have their forward ends located at positions rearward of those shown, provided that their length is sufficient to maintain the stream of cinders and gases away from the superheater tubes so that they clear the latter.

What I claim is:

1. In a fire tube boiler having a front tube sheet into which are connected a plurality of fire tubes and relatively large superheater flues disposed in horizontal and vertical alignment to form parallel rows with rows of fire tubes interspersed among and closely adjacent the rows of flues, a superheater header disposed forwardly of said tube sheet and above the uppermost row of flues and superheater tubes mounted in said flues and projecting forwardly therefrom and having upwardly bent end portions connecting with said header: a tubular deflecting shield mounted in alignment with each fire tube for receiving cinders therefrom and arranged to direct them to a point preventing their impingement upon the bent portions of said superheater tubes.

2. In a fire tube boiler having a front tube sheet into which are connected a plurality of fire tubes and relatively large superheater flues disposed in horizontal and vertical alignment to form parallel rows with rows of fire tubes interspersed among and closely adjacent the rows of flues, a superheater header disposed forwardly of said tube sheet and above the uppermost row of flues and superheater tubes mounted in said flues and projecting forwardly therefrom and having upwardly bent end portions connecting with said header: hollow deflecting shields each having a tubular portion fitting into a fire tube and extending forwardly therefrom for an ex-

tent sufficient to impose a directional force on cinders issuing from said flue to maintain them in a fixed path of travel until they pass the bent portions of said superheater tubes for preventing 5 impingement of the cinders thereon.

3. In a fire tube boiler having a front tube sheet into which are connected a plurality of fire tubes and relatively large superheater flues disposed in horizontal and vertical alignment to 10 form parallel rows with rows of fire tubes interspersed among and closely adjacent the rows of flues, a superheater header disposed forwardly of said tube sheet and above the uppermost row of flues and superheater tubes mounted in said flues and projecting forwardly therefrom and having upwardly bent end portions connecting 15 with said header; hollow deflecting shields each having a tubular portion fitting into a fire tube and merging into a vertically disposed flattened nozzle like end portion located in the free area between the adjacent bent portions of superheater tubes for deflecting the cinders issuing from the fire tube away from the sides of said bent portions of the superheater tubes.

20 4. In a fire tube boiler having a front tube sheet into which are connected a plurality of fire tubes and relatively large superheater flues disposed in horizontal and vertical alignment to 25 form parallel rows with rows of fire tubes interspersed among and closely adjacent the rows of flues, a superheater header disposed forwardly of said tube sheet and superheater tubes mounted in said flues and projecting forwardly therefrom and having bent end portions connecting 30 with said header: a tubular deflecting shield mounted in alignment with each fire tube for receiving cinders therefrom and arranged to direct them to a point preventing their impingement upon the bent portions of said superheater 35 tubes.

40 5. In a fire tube boiler having a front tube sheet into which are connected a plurality of fire tubes and relatively large superheater flues disposed in horizontal and vertical alignment to 45 form parallel rows with rows of fire tubes interspersed among and closely adjacent the rows of flues, a superheater header disposed forwardly of said tube sheet and superheater tubes mounted in said flues and projecting forwardly therefrom and having bent end portions connecting 50 with said header: and deflecting shields mounted forwardly of said tube sheet and so disposed with respect to said fire tubes and said superheater tubes as to direct cinders from said fire tubes to points preventing their impingement on 55 portions of said superheater tubes projecting from said flues.

EMANUEL RAWSON.
